UNITED STATES PATENT OFFICE.

ORANGE S. LEE, OF CLINTON, MASSACHUSETTS, ASSIGNOR TO THE CLINTON
WIRE CLOTH COMPANY, OF SAME PLACE.

COMPRESSION-ROLLER FOR WIRE-WARPING MACHINES.

SPECIFICATION forming part of Letters Patent No. 352,138, dated November 9, 1886.

Application filed August 23, 1886. Serial No. 211,609. (No model.)

To all whom it may concern:

Be it known that I, ORANGE S. LEE, of Clinton, in the county of Worcester, State of Massachusetts, have invented a certain new and useful Improvement in Compression-Rollers for Wire-Warping Machines, of which the following is a description sufficiently full, clear, and exact to enable any person skilled in the art or science to which said invention appertains to make and use the same, reference being had to the accompanying drawings, forming part of this specification, in which—

Figure 1 is an elevation representing the warp-beam with the roller in position for use, the "flare" of the grooves in the beam being distorted, or their walls abnormally inclined, in order to better illustrate the principle of the invention; Fig. 2, an end elevation of the roller detached; Fig. 3, a front elevation of the same, and Fig. 4 a vertical transverse section.

Like letters of reference indicate corresponding parts in the different figures of the drawings.

It is well known that in the mechanism employed in the manufacture of wire-cloth the beams of the warping-machines are usually grooved peripherally, or provided at regular intervals with annular flanges, which divide the surface of the beam into corresponding annular grooves, in which the wire is deposited as the beam is filled. In order to fill these grooves properly, a compressor is employed, which bears upon the wire as it is delivered to the beam, thereby compacting and evening the layers. This compressor usually consists of a roller, which is journaled horizontally in such a manner as to bear upon the layers of wire as they are formed in the groove, and when one groove is filled is moved to the next succeeding groove, and so on throughout the series; but as the grooves are sometimes constructed slightly narrower at the bottom than at the top, or one or both of their sides wear away by the action of the wire, thereby causing them to incline or the grooves to flare as they approach the periphery of the beam, a roller which fits the bottom of the groove will not be quite long enough to fit it when the groove is nearly filled with wire, and hence the wire, if very small or when comparatively fine, will

tend to "pile up" at the ends of the roller, or between the roller and the adjoining flanges, and produce bad work, the layers, more especially the outer ones, not being formed in 55 parallelism with the axis of the beam or properly evened and compressed.

My invention is designed to obviate this difficulty, and to that end I make use of an expandible or compensating compressor-roller, 60 the construction and operation of which will be readily understood by all conversant with such matters from the following explanation.

In the drawings, A represents a portion of the frame-work in which the warp-beam is 65 mounted; B, the beam, and C the roller.

The surface of the beam is divided by a series of annular flanges, *x*, which are of slightly greater diameter in cross-section at their bases than at their peripheries, into a corresponding 70 series of annular grooves, *m*, or grooves which are of slightly less diameter at the bottom than at the top.

Disposed in front of the beam, and nearly on a plane with its upper side, there is a horizontally-arranged rod, D, on which the sleeve E is fitted to slide. Said sleeve is provided with a pair of arms, *b b*, which project over the beam B, in the outer or free ends of which the roller C is horizontally journaled on the trunnions *f*.

The roller is constructed in two sections or halves, *d d*, each section being provided centrally on its outer face with a trunnion, *f*, and on its inner face with an annular groove, *z*, 85 and the two sections are connected by the bolt *k* and nut *l*, the bolt being inserted in holes which pass longitudinally through the trunnions, as best seen in Fig. 4, the holes being slightly larger than the bolt, thus permitting the sections to slide freely thereon.

A coiled spring, N, is disposed in the grooves *z* within the roller, said spring acting expansively to force the sections *d d* apart, but being sufficiently flexible to permit the roller to be 95 readily compressed laterally.

The inner faces of the sections *d*, between the grooves *z* and their peripheries, are mutually serrated, as shown at *v* in Fig. 3, the teeth of each section fitting loosely in the 100 spaces between the teeth of the opposite section, the object of the serrations being to in-

terlock the sections in such a manner as to cause them to revolve in unison, and at the same time not materially change the bearing or working surface of the roller.

5 In the use of my improvement the nut *l* is first so adjusted on the bolt *k* that when the roller is fully expanded it will fill the groove at the surface of the beam. The roller is then dropped into the groove *m* at the end of the beam, its weight causing the spring *N* to be compressed as the sections *d* slide down the inclined sides of the flanges *x* until it rests on the bottom of the groove. The wire is then wound onto the beam in the groove, and as the roller rises with each succeeding layer it is expanded by the spring *N*, thereby keeping it in constant contact with the adjoining flanges, and preventing the wire from overriding and piling up between the ends of the roller and the flanges in a manner that will be obvious to all conversant with such matters without a more explicit description.

Having thus described my invention, what I claim is—

20 1. A compression-roller consisting of the

sections *d*, provided with the trunnions *f* and the interlocking serrations *v*, the spring *N*, interposed between said sections, and the bolt *k*, extending through said trunnions and provided on opposite ends with a head and a nut, 30 respectively, substantially as described.

2. A compression-roller consisting of the sections *d*, provided with the trunnions *f*, the interior grooves *z*, surrounding said trunnions, and the interlocking serrations *v*, the spring *N*, 35 interposed between said sections, its ends resting within said grooves *z*, and the bolt *k*, extending through said trunnions and provided on opposite ends with a head and a nut, respectively, substantially as described. 40

3. The expansible roller *C*, provided with end trunnions, in combination with the rod *D* and the sleeve *E*, sliding thereon, and having arms *b*, provided with eyes, within which said trunnions are journaled, substantially as described. 45
